RETINOSCOPE

James H. Grout, Chicago, Ill.

Application October 10, 1938, Serial No. 234,265

4 Claims. (Cl. 88—20)

This invention relates to improvements in diagnostic instruments, such as retinoscopes, and the like, which are provided with a small aperture or sight opening and have an illuminating attachment usually consisting of a small incandescent lamp bulb whose rays are reflected by a mirror in front of the sight opening, the mirror being provided with a sight opening or clear space in alignment with the sight opening in the instrument so as not to impair the line of vision. One of the objects of the invention is to provide in a device of this character improved means whereby the axis of an astigmatic eye may be determined and the various meridians scanned, the fundus of the eye being illuminated by two streaks or bands of light at substantially right angles to each other, the horizontal streak serving to scan the vertical meridians and the horizontal meridians being scanned by the vertical streak, that is, after neutralizing the axis meridian with one streak, the second meridian is neutralized with the other streak which is exactly 90° away, and at any time during the examination the operator may always scan the other meridian by merely observing with the other streak.

A further object is to provide an improved device of this character embodying means whereby the necessity of readjustment each time the grip is loosened, the hand moved, or the instrument laid down for phoropter adjustment will be obviated, thereby resulting in greater rapidity and accuracy in findings, and the axis will not be found by approximation or trial and error method.

A further object is to provide in a device of this character improved means whereby the rotative movement as well as the axial adjustment or movement of the light streaks will be effected by the movement of finger engaging portions movable only in directions lengthwise of the longitudinal axis of the instrument or supporting handle.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a view in elevation of an instrument of this character constructed in accordance with the principles of this invention, and as taken from the patient's side of the instrument.

Figure 2 is a longitudinal sectional view taken on line 2—2 of Figure 1 on an enlarged scale.

Figure 3 is a detail sectional view as taken on line 3—3 Figure 2 on an enlarged scale.

Figure 4 is an irregular sectional view, on an enlarged scale, taken on line 4—4 Figure 2.

Figure 5 is a front elevation of a portion of the instrument or handle showing a scale or graduation in conjugation with which the light streaks are operated.

Referring more particularly to the drawing, the numeral 10 designates generally a handle or support for the instrument which is hollow and which may be of any desired size and configuration. The upper end of the handle is preferably shaped to form a circumferential shoulder 12 spaced from the extremity of the handle and in such extremity is arranged a lens 13.

The handle 10 is preferably of a sectional construction, the upper section 14 thereof telescoping into the lower section and being provided with a peripheral shoulder 15 which abuts the adjacent extremity of the lower section, thereby enabling the operator to have ready access to the mechanism within the handle.

Disposed within the handle is a hollow or tubular member 16 supported for longitudinal movement in a bearing 17 which bearing is suitably supported and holds the tubular member 16 central with respect to the handle.

Into upper end of the tubular member 16 there is threaded an incandescent lamp or bulb 20. The numeral 21 designates a screen which is secured in a cap 22, the cap being adapted to be sleeved over the extremity of the tubular member 16 so that its extremity will abut the circumferential shoulder 19. This will permit the cap and screen 21 to be readily removed when desired to replace the lamp or bulb 20 if necessary.

The screen 21 is preferably formed of frosted glass but any other suitable opaque material may be employed. The entire screen is opaque with the exception of two narrow strips or portions 23—24, which latter are translucent so as to permit the rays of light from the bulb or lamp 20 to pass through the screen to the lens 13. The translucent strips or portions 23—24 are arranged at right angles to each other and will produce ribbon shaped beams at right angles to each other. If desired, color indications 25—26 may be associated with the respective strips 23—24.

The lower portion of the tubular member 16 is provided in its periphery with elongated teeth

27, any number of which may be provided, and these teeth may be of any desired length.

Meshing with the teeth 27 are teeth 28 of a gear or rotatable member 29. This member 29 is provided with reduced extremities 30, which are journaled in bearings 31 carried by a bifurcated member 32 which latter is secured to the casing of the lower section of the handle 10. The gear 29 standing within the bifurcation of the member 32 will be held against movement in the direction of its axis but will be adapted for free rotation and when rotated will impart a corresponding rotation to the tubular member 16 as well as the screen 21 so as to permit the beams of light of ribbon formation to be rotated for the purpose of scanning the various meridians of the eye.

The gear 29 is actuated by means of a finger engaging button 33 which is disposed outside of 20 the handle. This button is connected to a bar or rod 34, a portion of which extends in a direction lengthwise of the axis of the gear 29 and is twisted or given a spiral formation as indicated at 35. The rod 34 passes through an opening 36 25 in the gear 29 and fits the opening with the result that when the finger engaging portion 33 is moved lengthwise of the handle the rod 35 will be similarly moved and as it passes through the gear 29 it will cause the gear to rotate, thereby rotating the tubular member 16 and with it the screen and the beams of light.

Any suitable friction creating means, such as indicated as at 37, may be provided so as to maintain the finger engaging portion 33 and the rod 35 as well as the gear 29 in their adjusted positions.

Arranged along the outside of the handle 10 are graduations 38 with which pointers 39 on the finger engaging portion 33 co-operate. These 40 graduations or indications are arranged so that the beams of light will be in conjugation therewith.

The graduations or indications are preferably indicated by the same color as the color which is 45 associated with the respective ribbons of light.

The tubular member is preferably of a sectional construction and is provided with the reduced extremity 40 providing a shoulder 41. This reduced extremity is telescoped into another tubular section 42 that is provided with a slot 43 50 through which a fastening screw 44 passes and engages the tubular member 16 to hold the sections of the tube together but allows the sections to be rotated one with respect to the other.

The tubular section 42 telescopes into another tubular section 45 within the handle, all serving 55 as a bearing for supporting the tubular member 16—14 for longitudinal movement in the handle 10. A contact terminal 46 carried by an insulating member 47 is arranged in the tubular member 42 and an electrical connection 48 is provided between the terminals 46 and the lamp 20.

Connected to this section 42 is a handle 48 which projects through a slot 49 in the handle 60 65 and by means of which the operator may move the tubular member 16 together with the lamp bulb 20 and the screen 21 longitudinally in the handle so as to move the screen 21 to the desired distance toward or away from the lens 13.

During this longitudinal movement of these parts the elongated teeth 27 on the section 16 will be moved with respect to the teeth 28 on the gear 29 which latter is held against bodily movement.

A plug 50 on the end of a conductor 51 forms

a cap for the end of the handle 10 and also a means of electrically connecting the device to a source of supply of current.

A hood 52 is sleeved over the end of the handle so as to abut the shoulder 12 and within the hood 5 is arranged an inclined mirror 53 provided with a clear space, or if desired an opening 54 arranged in alinement with a sight opening 55, and these two openings are also in register with an opening 56 through which the beams of light are reflected 10 into the patient's eye.

It will be noted that the fundamental difference between the present invention and the devices heretofore employed is the fact that two streaks of light are reflected in the form of an L and 15 which are 90° apart and that the scale which is provided on the body of the instrument with a movable indicator gives the meridian in which either streak is being moved or is lying.

In use when the meridian indicator is moved 20 to the top of the scale, the vertical and horizontal meridians are scanned, the vertical being scanned with the horizontal streak or ribbon and the horizontal meridian being scanned by the vertical streak. This obviates the necessity of a 25 sleeve rotation.

After producing "against" motion in one meridian and near "neutral" in the other, the axis will be found and this becomes a simple process with these right angularly disposed ribbons of 30 light. One of the ribbon streaks is moved through the meridians having "with," or the least "against" motion, until the reflex is seen to move with no obliquity. In the case of the high astig- 35 mope the instrument is changed into a "concave 35 mirror" scope by moving the finger engaging portion 33 downwardly and with the other streak focusing a band in the eye that coincides with the streak across the eye. In either case the axis is now given accurately on the instrument. The 40 meridian indicator now remains set in this position through the entire examination. After neutralizing the axis meridian with one streak, the second meridian is neutralized with the other which is set exactly 90° away, and the eye is cor- 45 rected.

At any time during the examination the operator may always scan the other meridian by merely observing with the other streak.

This technique parallels the present "streak" 50 technique, but differs in that the axis is not found by approximation or trial and error method, and that a sleeve need not be rotated from one principal meridian to the other and results in greater accuracy in the present invention. 55

By the arrangement of the two streaks of light at an angle of 90° with respect to each other renders it possible to provide an accurate scale which will be only about half the length of the ordinary scale in instruments employing only 60 a single straight ribbon of light.

While the preferred form of the invention has been herein shown and described, it is to be understood that various changes may be made in the details of construction and in the combination and arrangement of the several parts within the scope of the claims, without departing from the spirit of this invention.

What is claimed as new is:

1. In a retinoscope of the character described, 70 a handle, a lamp support, a lamp rotatably mounted upon the support, means for rotating said lamp with respect to the handle, the last said means embodying, teeth on the said support, a gear meshing with the teeth, a finger engaging 75

element slideable lengthwise of the support, and a stem to which the said element is connected, said stem being axially twisted and passing through the gear, whereby when the stem is moved longitudinally through the gear the latter will be rotated.

- 6 2. In a retinoscope of the character described, a handle, a lamp support, a lamp rotatably supported on said support, means for rotating the lamp with respect to said support, the last said means embodying, teeth on the support, a gear meshing with the teeth, a finger engaging element slideable lengthwise of the handle, a stem to which the said element is connected, said stem being axially twisted and passing through the gear, whereby when the stem is moved longitudinally through the gear the latter will be rotated, and means for moving the said lamp support in directions lengthwise of the axis of said handle, 15 the said teeth being elongated, whereby the support may be longitudinally moved with respect to said gear.

- 10 3. In a retinoscope, a handle, a light bulb supported thereby, a reflector also supported by the handle and positioned to receive the rays from the bulb, a screen disposed between the light bulb and said reflector and mounted for rotation and for bodily adjustment with respect to the re- 15

flector, said screen being opaque and provided with narrow translucent portions arranged at substantially right angles, one forming a continuation of the other, means for axially rotating said screen, and indicating means with which a portion of the last recited means co-operates to indicate the extent of rotation of said screen, the said indicating means and the said translucent portions of said screen being in conjugation.

- 15 4. In a retinoscope, a handle, a light bulb supported thereby, a reflector also supported by the handle and positioned to receive the rays from the bulb, a screen disposed between the light bulb and said reflector and mounted for rotation and for bodily adjustment with respect to the reflector, said screen being opaque and provided with narrow translucent portions arranged at substantially right angles, one forming a continuation of the other, means for axially rotating said screen, and indicating means with which a portion of the last recited means co-operates to indicate the extent of rotation of said screen, the said indicating means and the said translucent portions of said screen being in conjugation and provided with corresponding color designations.

20 25 JAMES H. GROUT.
